UNITED STATES PATENT OFFICE.

RAYMOND W. HODGETTS, OF SPRINGFIELD, MASSACHUSETTS, ASSIGNOR TO THE ALLEN COMPANY, A COPARTNERSHIP CONSISTING OF HAROLD W. HODGETTS AND CLARENCE W. ALLEN, BOTH OF SPRINGFIELD, MASSACHUSETTS.

DESIGN FOR A CASKET HANDLE.

Application filed October 30, 1922. Serial No. 4,163. Term of patent 3½ years.

To all whom it may concern:

Be it known that I, RAYMOND W. HODGETTS, a citizen of the United States of America, residing at Springfield, in the county of Hampden and Commonwealth of Massachusetts, have invented a new, original, and ornamental Design for Casket Handles, of which the following is a specification, reference being had to the accompanying drawing, forming part thereof.

Fig. 1 is a plan view of the casket handle showing my new design, and Fig. 2 is a section thereof on the line 2—2 of Fig. 1.

I claim—

The ornamental design for a casket handle as shown.

RAYMOND W. HODGETTS.
